SPACER FOR A GRILLE

Edward C. Hallock, 86 Woodland Ave., Summit, N.J.

Filed May 8, 1962, Ser. No. 70,030

Term of patent 14 years

(Cl. D54—2)

I claim:

The ornamental design for a spacer for a grille, as shown.
